UNITED STATES PATENT OFFICE.

LOUIS HAMMOND, OF NEW HAVEN, CONNECTICUT.

DIE FOR ROLLING AXES.

SPECIFICATION forming part of Letters Patent No. 278,544, dated May 29, 1883.

Application filed February 19, 1883. (No model.)

To all whom it may concern:

Be it known that I, LOUIS HAMMOND, of New Haven, in the county of New Haven and State of Connecticut, have invented a new Improvement in Dies for Rolling Axes; and I do hereby declare the following, when taken in connection with accompanying drawings and the letters of reference marked thereon, to be a full, clear, and exact description of the same, 10 and which said drawings constitute part of this specification, and represent, in—

Figure 1, a transverse section, the dies as commencing the rolling operation upon the sides of the ax; Fig. 2, the same, showing the 15 completion of that operation; Fig. 3, a transverse section of the dies *a b* midway of their length; Fig. 4, a transverse section of the rolls and dies for shaping the ax transversely, and in the position of commencing the operation; 20 Fig. 5, a transverse section of the dies *ef* near their finishing ends; Fig. 6, a transverse section of the rolls, showing the dies as just finishing their work upon the blank.

This invention relates to an improvement in 25 dies for rolling or shaping axes; and it consists in dies, as hereinafter described, arranged in rolls, whereby the blank introduced between the dies at the proper time is brought to the required shape.

30 A represents the lower and B the upper of a pair of rolls geared together and working in the usual manner of rolls for similar purposes. At corresponding points in the surface of each of the rolls, respectively, is a die, *a b*. These 35 dies are secured to their respective rolls, and so that the two advancing ends *d* of the two dies, when they stand directly over each other, will grasp the blank introduced between them, as seen in Fig. 1. From that point the shape 40 of the dies is the reverse of the two faces or sides of the ax, as seen in transverse section, Fig. 3, except that they are curved to corre-

spond to the rolls, and so that after the blank has been grasped and the rolls revolving, as indicated by arrows, the blank introduced will 45 be forced backward with the rolls, the metal squeezed between the two dies and brought into shape, as seen in Fig. 2. After thus rolling and shaping the two sides, a transverse shaping is required, and this is performed by 50 similar rolls, C D, Fig. 4, having in their faces, respectively, dies *e f*, the shape of which corresponds, respectively, to the front and back of the ax, as seen in transverse section, Fig. 5. The blank, rolled in the previous operation, being placed between them, as indicated in Fig. 4, so that the rolling will commence at the head end of the blank, will be forced backward, and the sides shaped, as indicated in 55 Fig. 6.

60 By this process of rolling, a very large proportion of the work heretofore required in finishing axes is saved, and more perfect work is performed, because when once the dies are right all the axes rolled by them will be of that 65 exact and proper shape. Hence there will be a greater uniformity in the axes than can be produced by the usual methods of forging.

I claim—

The herein-described dies for rolling axes, 70 consisting of the series of dies *a b* and *ef*, the cavities of the first pair of dies corresponding to the two sides of the ax, the second pair corresponding to the back and front of the ax, and the respective dies shaped to 75 conform to the rolls in which they are arranged, whereby the rotation of the rollers carrying the dies shapes the ax upon its sides, and upon its back and front, substantially as described.

LOUIS HAMMOND.
